US00D617058S

(12) **United States Design Patent**
Akrey

(10) **Patent No.:** **US D617,058 S**
(45) **Date of Patent:** **** Jun. 1, 2010**

(54) **ANCHOR FOR A PET RESTRAINT**

(76) Inventor: **Francis Gregory Akrey**, 3563 Old Conejo Rd., Newbury Park, CA (US) 91320

(**) Term: **14 Years**

(21) Appl. No.: **29/345,740**

(22) Filed: **Oct. 21, 2009**

(51) **LOC (9) Cl.** **30-09**

(52) **U.S. Cl.** **D30/154**

(58) **Field of Classification Search** **D30/154, D30/199, 160, 151, 153; D6/608, 609, 613, D6/614, 603, 583, 588-591, 597, 598, 611, D6/601; 119/174, 850, 650, 621, 600, 602, 119/707-712, 786-788, 791, 780, 782, 769-771, 119/795, 856; D29/118; D24/207, 208, D24/200, 206; D7/388; 5/417; 219/759, 219/730, 528, 529; 426/241; 99/DIG. 14; D5/62; 607/96, 108-111, 104; 52/155, 166, 52/157, 162, 163; D28/79, 73, 76-78, 83; D3/216, 223, 271.1, 234-236, 238, 248, 205, D3/295, 301, 703.6, 203.1, 294; D11/81, D11/103; D9/600, 629, 220/4.26, 4.27; 132/286, 287, 293-307, 314-318; 206/581, 206/823, 37, 315.1, 6.1; D21/385**

(57) **CLAIM**

The ornamental design for an anchor for a pet restraint, as shown.

DESCRIPTION

FIG. 1 is a perspective view of an anchor for a pet restraint embodying my new design wherein an animal and leash are shown in phantom and form no part of the claimed design;

FIG. 2 is a top, front and right-side perspective view of the anchor for a pet restraint;

FIG. 3 is a front elevational view thereof;

FIG. 4 is a rear elevational view thereof;

FIG. 5 is a right-side elevational view thereof, the left-side elevational view being a mirror image;

FIG. 6 is a top plan view thereof; and,

FIG. 7 is a bottom plan view thereof.
